UNITED STATES PATENT OFFICE.

RACHEL KELSALL, OF LONDON, ENGLAND.

WORKBOX FOR DOMESTIC USE.

1,408,093.

Specification of Letters Patent. Patented Feb. 28, 1922.

Application filed December 21, 1920. Serial No. 432,293.

To all whom it may concern:

Be it known that I, RACHEL KELSALL, a subject of the King of Great Britain, residing at 9, Messrs. Cox & Co., J Department, 5 16 Charing Cross, London, S. W. 1, in the county of London, in England, have invented a new and useful Improvement in Workboxes for Domestic Use, of which the following is a specification.

10 The invention relates to work boxes for containing tapes, silks, cottons, buttons, pins, and the like, for general domestic use.

15 My invention consists of improvements, such as construction of feet beneath the platform formed by a continuation of the sides of the chest of drawers each foot having two horizontal slots cut therein. Transverse slots are made in the platform in order to receive the feet and the end of the vertical board. 20 Near the end of this said board are cut two horizontal slots corresponding with the slots provided in the feet above described. The object of the slots in the vertical board and feet is to receive two strips or laths for 25 keying rigidly together the feet and the vertical board and the work box platform. The feet above described are an extension of the sides of the chest of drawers and are fixed to the underside of the platform by 30 means of angle plates secured by rivets. The body cover may be transposed into a basket for holding needle work by means of the cover or top being made removable so that it can be removed and inserted in the bottom 35 of the body cover, the said body having two loosely pivoted handles.

In the accompanying drawings, Fig. 1, is a front elevation of the chest of the drawers; Fig. 2, is a side elevation of Fig. 1; Fig. 3, 40 is a plan of the bottom of the platform; Fig. 4, is a plan of the top of Fig. 1; Fig. 5, is an elevation of the body cover with loosely 45 pivoted handles, and Fig. 6, is a sectional elevation of the body cover having the removable top or cover inserted in its base in order to be used as a basket for holding needle work.

50 My invention consists of such improvements that are used in conjunction with my former invention claimed and described in my specification, Serial No. 319,022, dated August 2nd, 1919.

In Fig. 4, is shown the division *a* in which the movable board 1 with spikes is inserted, the said board resting against the solid back 55 *b* of the chest of drawers. Adjoining the bottom end of the movable board 1, I cut two slots *c* in order to be keyed to the platform *d* by means of longitudinal strips or laths *e* as shown in Figs. 1, and 3. 60

In Figs. 1, 2, and 3, is shown the platform *d* mounted on feet *g* formed by the extension of the sides 2, and 3, passing through slots 4, and 5, cut in the platform *d*, the said feet *g* being fixed to the platform *d* by means of 65 angle plates *f* riveted together. These said feet *g* are provided with two slots *h* in each in order to receive the strips or laths *e* for keying up the bottom end of the feet *g* and the movable vertical board 1 when it is 70 passed through the transverse slot *i* cut centrally in the platform *d* thus fixing the feet *g* and board 1 rigidly to the platform *d*.

In another modification the body cover *i* is transposed into a basket as shown in Fig. 75 6, by means of the removable top or cover *j* being inserted rigidly but removably into the bottom of the body cover *i* the said body cover *i* having two loosely pivoted handles *k*. This aforesaid basket is intended to hold 80 or contain any needle work or the like.

I claim:

1. A work box provided with a chest of drawers and a platform, the platform having a middle slot and end slots; feet on the 85 chest of drawers, said feet passing through the end slots of the platform and being themselves provided with transverse slots below the platform; a board extending vertically through the middle slot of the platform and 90 having transverse slots therethrough below the platform and strips passed through the slots in the feet and the vertical board.

2. A work box provided with feet, a platform fixed to the underside of the box by 95 means of angle plates, and a vertically arranged board having slots in the lower end thereof; the feet having transverse slots corresponding to the slots in the board and strips inserted through the slots in feet and 100 board.

RACHEL KELSALL.
